MONNIN & BOOTH.

Fastening Lanterns.

No. 11,437.

Patented Aug. 1, 1854.

UNITED STATES PATENT OFFICE.

CHARLES MONNIN AND WILLIAM M. BOOTH, OF BUFFALO, NEW YORK.

FASTENING LANTERNS.

Specification forming part of Letters Patent No. 11,437, dated August 1, 1854; Reissued January 30, 1855, No. 11,437.

To all whom it may concern:

Be it known that we, CHARLES MONNIN and WILLIAM M. BOOTH, of Buffalo, in the county of Erie and State of New York, have 5 invented a new and useful Improvement in Lanterns for General Use; and we do hereby declare that the following is a full description of the construction and operation of the same, reference being had to the accompanying drawings, making a part of this specification, in which—

Figure I is a vertical section of lantern with lamp inserted; Figs. II and III, transverse sections, and Fig. III a perspective view.

The nature of our invention consists in affixing a cylindrical ring inclosing two metallic clamps, to the lower part of the lantern in such a manner as to admit of the lamp being placed in or taken out of the lantern at will by a circular movement of the ring and holding it securely in its place when inserted, and also of attaching a saucer or drainer around the lamp for the waste oil in combination with this improvement.

In order to a better understanding of this application, we proceed to describe the lantern with its appendages.

The lantern may be of any desirable form, the globe of glass, the lamp, frame and guards of metal.

A—B, Fig. I, is the cylindrical ring inclosing the clamps, which work through two apertures b b, Figs. II and III.

D, Fig. I, represents the saucer.

Fig. II represents the ring C, with the clamps a, a, drawn in, that is, when the lamp and lantern are detached.

Fig. III is a representation of the clamps a, a, extended into the groove through the apertures b, b, and holding the lamp in its place.

To connect the lamp and lantern, cover the former with the lantern and turn (screw) the ring forward. This pushes the clamps with an eccentric direction into the groove of the lamp and keeps it secure, as in Fig. III. To disconnect them, turn (unscrew) the ring backward. This movement brings the clamps back out of the groove into the ring, as in Fig. II.

What we claim as our invention, and which we desire to secure by Letters Patent, is—

The application to lanterns of the before-mentioned cylindrical or hollow ring, inclosing one or more metallic clamps or dogs, which move horizontally through apertures into a groove as herein described and set forth.

CHARLES MONNIN.
WILLIAM M. BOOTH.

In presence of—

R. I. COMPTON,
HENRY C. CHOWRUJS.
